Des. 221,378
Patented Aug. 10, 1971

221,378

RACING CAR BODY

Michael D. Williams, Roselle, Ill., assignor to Armco
Steel Corporation, Middletown, Ohio

Filed Nov. 10, 1969, Ser. No. 20,025

Term of patent 14 years

Int. Cl. D12—08

U.S. Cl. D14—3

FIG. 1

FIG. 2

FIG. 3

FIG. 5

FIG. 4

FIG. 1 is a side elevational view of a racing car body showing my new design.

FIG. 2 is a front elevational view of the same.

FIG. 3 is a rear elevational view of the same.

FIG. 4 is a top plan view of the same; and

FIG. 5 is a perspective view of the same.

I claim:

The ornamental design for a racing car body, as shown.
